UNITED STATES PATENT OFFICE.

HOMER C. HIATT, OF BLISS, OKLAHOMA.

ENGINE-INTAKE HEATER.

1,214,784.

Specification of Letters Patent. Patented Feb. 6, 1917.

Application filed November 27, 1915. Serial No. 63,786.

To all whom it may concern:

Be it known that I, HOMER C. HIATT, a citizen of the United States, residing at Bliss, in the county of Noble and State of Oklahoma, have invented new and useful improvements in Engine-Intake Heaters, of which the following is a specification.

This invention relates to fuel heaters, the object in view being to provide a device of the class referred to which is in the nature of an attachment to the intake pipe or manifold of an internal combustion engine, the same serving to thoroughly heat the explosive mixture at a point between the carbureter and the combustion chamber of the cylinder or cylinders whereby economy is effected in the consumption of fuel oil, the rapid accumulation of carbon prevented and higher efficiency of the engine obtained.

20 A further object of the invention is to provide in conjunction with such heater, means for releasing exploding mixture in case of back fire from the engine. With the above and other objects in view, the invention consists in the novel construction, combination and arrangement of parts, as herein described, illustrated and claimed.

In the accompanying drawings:—Figure 1 is a longitudinal section through the intake heater of this invention, showing certain parts in elevation. Fig. 2 is a cross section on the line 2—2 of Fig. 1.

Referring to the drawings, 1 designates the intake pipe of an internal combustion engine which, in carrying out the present invention, is divided to form sections 1 and 1' the ends of which are located in spaced relation to each other and threaded to receive the oppositely located internally threaded heads 2 and 3 of an outer shell or cylindrical heater body 4 which is shown as provided adjacent to one end thereof with an exhaust inlet 5 and at the opposite side and near the opposite end thereof with an exhaust outlet 6. The body 4 and the heads 2 and 3 flanged as shown and fastened together by bolts 7 or the equivalent thereof.

Extending centrally and longitudinally of the outer shell 4 is an inside tubular shell 8 which contains a stationary spiral deflector 9 resembling an auger bit in shape, the said deflector 9 being secured in a stationary

position within the shell 8 by any suitable means such, for example, as by making the deflector 9 of such external diameter as to fit tightly against the inner wall of the shell 8. The shell 8 is fastened at its opposite extremities to the end walls of the outer shell 4 so that the exhaust gases cannot obtain entrance to the shell 8.

60 The pipe 1 adjacent to the receiving end of the shell 4 is formed with an outlet 10 which is normally closed by an externally arranged valve 11 held tightly to its seat by means of a coiled expansion spring 12 encircling the stem 13 of the valve 11, the stem passing through a suitable guide 14 fixedly attached to the pipe 1. In case of back fire, the valve 11 automatically opens to allow the expanding mixture to be liberated 70 to the atmosphere without reaching the carbureter.

By means of the construction and arrangement above described, the explosive mixture, which is ordinarily cold as it is drawn through the intake pipe, is thoroughly heated before reaching the combustion chamber or chambers of the engine and the particles of fuel oil are thoroughly agitated and broken up, and the mixture vaporized. 80 It will, of course, be understood that the exhaust pipe (not shown) is also divided so that the heater body 4 may be incorporated therein. Thus the heat of the exhaust gases from the engine is utilized for heating the incoming mixture. The invention is particularly valuable when used in conjunction with kerosene or other fuel oils of a lower grade than gasoline which is at present so universally used, although the device 85 will also effect a considerable economy in the consumption of gasoline and also by producing a better mixture and heating the same add to the efficiency of the engine and also reduce the rapid accumulation of carbon within the combustion chamber or chambers of the engine.

Having thus described my invention, I claim:—

A heater of the class specified, comprising an outer tubular shell having inlet and outlet openings adjacent to the opposite ends thereof, an inside tubular shell of less external diameter than the internal

diameter of the outer shell and concentric therewith, heads at opposite ends of the outer and inner shells leaving an annular exhaust circulation space between the outer 5 and inner shells, said heads being centrally extended outwardly and bored to receive the opposite extremities of said inside shell and also to receive pipe inlet and outlet

connections, and a fixed spiral deflector within said inner shell.

10

In testimony whereof I affix my signature in presence of two witnesses.

HOMER C. HIATT.
